CLAIM

The ornamental design for a telephone, as shown and described:

DESCRIPTION

FIG. 1 is a side elevation of a telephone showing my new design;

FIG. 2 is a front top perspective view thereof;

FIG. 3 is a top perspective taken at an alternate position from that illustrated in FIG. 2;

FIG. 4 is a bottom plan view thereof;

FIG. 5 is a top front perspective view of a modified form of telephone instrument illustrated in FIG. 2;

FIG. 6 is a top plan view thereof;

FIG. 7 is a rear elevation thereof;

FIG. 8 is a side elevation thereof;

FIG. 9 is an elevation as seen from the opposite side of FIG. 8;

FIG. 10 is a front elevation thereof; and

FIG. 11 is a bottom plan view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.
